PUMP

Frank H. P. Sully, La Mirada, Calif., assignor to Western Brass Works, Los Angeles, Calif., a corporation of California

Filed Apr. 8, 1963, Ser. No. 271,187
9 Claims. (Cl. 103—120)

This invention relates to a pump and more particularly relates to a variable flow pump.

In many pumping systems and applications it is desirable to be able to continuously vary the flow rate of a pump over a reasonably wide range and with extreme accuracy. Inasmuch as many of these applications involve the pumping of chemicals, other corrosive materials, slurries, or other non-homogeneous streams, it is also desirable that such a pump be easy to disassemble and reassemble so that the pump may be cleaned in a short time. According to the present invention, such a variable flow pump is provided, the pump having a pumping chamber which can be adjustably positioned relative to the impeller whereby the flow rate of the pump can be varied. The various components of the pump are held in place by a locking bar which can be swung out of position to facilitate the cleaning of the pump.

It is therefore an object of the present invention to provide a pump having a continuously variable flow rate.

It is also an object of the present invention to provide such a pump wherein the pumping chamber is continuously adjustable relative to the impeller.

It is another object of the present invention to provide such a pump wherein the position of the pumping chamber is laterally adjusted by rotating an adjusting plate mounted adjacent the chamber.

It is a further object of the present invention to provide such a pump which can be easily assembled and disassembled, and in which the various components are held in place by means of a locking bar.

These and other objects and advantages of the present invention will become more apparent upon reference to the accompanying description and drawings in which:

FIGURE 1 is a side elevation of the pump of the present invention;

FIGURE 2 is a front view of the pump of the present invention taken along lines 2—2 of FIGURE 1;

FIGURE 3 is a sectional view taken along lines 3—3 of FIGURE 2;

FIGURE 4 is a sectional view taken along lines 4—4 of FIGURE 2;

FIGURE 5 is a view, partly in section, taken along lines 5—5 of FIGURE 3;

FIGURE 6 is a view similar to FIGURE 5 but with the elements thereof in different positions;

FIGURE 7 is a top plan view of the pump of the present invention taken along lines 7—7 of FIG. 1;

FIGURE 8 is a view, partly in section, taken along lines 8—8 of FIGURE 1;

FIGURE 9 is a view, partly in section, taken along lines 9—9 of FIGURE 1;

FIGURE 10 is an exploded perspective view of a portion of the pump of the present invention; and

FIGURE 11 is an exploded perspective view of another portion of the pump of the present invention.

Referring now to the several figures, there is shown a pump 10 mounted on and driven by an electric motor 11. The pump 10 is mounted on the motor 11 by means of an L-shaped supporting plate 12 having a base 13 which may be fastened to any suitable support by means of holes 14, and an upstanding leg 15 to which the pump is fastened. The supporting plate 12 is affixed to the motor 11 by means of spacers 16 and bolts 17. The upstanding leg 15 is provided with a pair of de-

2

scending tabs 18 in which are mounted the ends of a locking bar 19 which is used to maintain the pump 10 in position on the leg 15.

The pump 10 includes a rear plate 21 held in place by means of a pair of pins 22 extending outwardly from the upstanding leg 15, a guide plate 23 also mounted on the pins 22 and having a generally rectangular aperture 24 therein, and a housing 25 having a pair of shoulders 26 which fit into the aperture 24 and an O-ring 27 which forms a seal with the rear plate 21. The inner walls of housing 25 and rear plate 21 thus form a pumping chamber 28. A cap or front plate 29 is positioned over the housing 25 and is held in place by means of a boss 30 which cooperates with a slot 31 in the housing 25. The cap 29 is provided with a groove 32 for receiving the locking bar 19, the bar 19 being provided with a snap spring portion 33 for this purpose.

The cap 29 is further provided with inlet and outlet ports 34 and 35 around which are positioned O-rings 36 to form a seal with inlet and outlet openings 37 and 38 in the face of the housing 25. The outlet port 35 is provided with a conventional check valve 39 which comprises a semi-spherical member 40 biased against the outlet passageway in the face plate of the housing 25 by means of a spring 41.

Positioned around the housing 25 is an adjusting plate 44 having a central opening 45 for receiving the housing 25 and an adjusting slot 46 formed therein. As can be seen, the slot 46 is generally arcuate but is eccentric relative to the central opening 45, and cooperates with a pin 47 to cause the adjusting plate 44 to move in a downward direction when it is rotated counterclockwise. One end of the pin 47 is threaded for making threaded engagement with suitable holes in the guide plate 23 and rear plate 21, while the other end is provided with an expanded portion or knob 48 which serves to lock the adjusting plate 44 against the guide plate 23.

An impeller 51 is mounted in the chamber 28 on the drive shaft 52 of the electric motor 11 which shaft extends through an aperture 53 in the rear plate 21. A resilient washer 54 is positioned in this aperture to form a seal about the shaft 52. The impeller is mounted on the shaft 52 by means of a keyed sleeve 55 which cooperates with a similarly keyed portion 56 of the shaft 52. The impeller 52 is provided with a plurality of flexible blades which extend outwardly from a hub 58 and whose outer ends engage the inner surface of the housing 25. As can be seen from FIGURE 5, the blades 57 are sufficiently long so that they are substantially flexed when the shaft 52 is coaxial with the housing 25.

The operation of the pump of the present invention will now be described, with particular reference to FIGURES 5 and 6. As can be seen in FIGURE 5, when the adjusting plate 44 is turned as far in the clockwise direction as the slot 46 and pin 47 will permit, the shaft 52 and hence the impeller 51 will be coaxial with the housing 25. Each of the blades 57 will thus be continuously flexed the same amount as the shaft rotates and the volume of each of the chambers defined by two blades, the hub 58 and the inner wall of the housing 25 will be equal. The pressure at the outlet port 35 will thus be the same as the pressure at the inlet port 34 and the pump will be pumping at a minimum rate.

When, however, the adjusting plate 44 is turned in a counterclockwise direction, the action of the pin 47 on the camming surface of the slot 46 causes the adjusting plate to move vertically downward. Since the adjusting plate surrounds the housing 25, vertical movement of the adjusting plate 44 is transmitted to the housing 25 and it also moves downwardly in the aperture 24 of the guide plate 23.

The shaft 52, however, is fixed and thus the pumping chamber 28 defined by the housing 25 moves relative to the impeller 51. When the adjusting plate 44 has been rotated as far as possible in the counterclockwise direction, the various elements are positioned as shown in FIGURE 6. In this figure, it can be seen that the impeller 51 is now eccentrically located in the chamber 28 with the result that the blades 57 extend almost radially in the lower part of the chamber but are severely bent over in the upper part of the chamber. The volume of the chamber formed by the blades over the inlet port thus is greater than that formed by the blades over the outlet port and thus the fluid will be expelled from the outlet port at a greater rate of flow.

The pump of the present invention is particularly useful in pumping chemicals or other materials of a corrosive or slurry composition as it can quite easily be taken apart and cleaned. To clean the various components of the pump, it is only necessary to free the locking bar 19 from the locking groove 32 in the cap 29 and pivot the locking bar away from the pump structure. The cap 29 and housing 25 can then be removed for cleaning. The remainder of the pump assembly can be made available for cleaning by removing the pin 47 and lifting the guide plate 23 and rear plate 21 off of the pins 22. Reassembly of the pump is equally as simple and convenient and enables the pump to be cleaned quickly, thereby reducing the pumping system down time to a minimum.

The invention may be embodied in other specific forms not departing from the spirit or central characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

I claim:

1. A variable flow pump comprising:
a plate having a generally rectangular aperture therein;
a housing slidably mounted in said generally rectangular aperture whereby said housing may move in said aperture relative to said plate, said housing having a pumping chamber therein and inlet and outlet openings communicating with said chamber;
a driving shaft extending through said aperture in said plate into said pumping chamber;
an impeller mounted on said shaft in said chamber, said impeller having a plurality of radially extending flexible blades, said blades being in engagement with, and flexed by, the interior wall of said housing;
an adjusting plate mounted on said plate, said adjusting plate having an aperture therein for receiving said housing; and
means cooperating with said adjusting plate and said plate to cause said adjusting plate and said housing to move laterally with respect to said plate when said adjusting plate is rotated.
2. A variable flow pump comprising:
a supporting plate for supporting said pump;
a rear plate mounted on said supporting plate, said rear plate having an aperture therein;
a guide plate mounted on said rear plate, said guide plate having a generally rectangular opening formed therein;
a housing slidably mounted in said generally rectangular opening whereby said housing may move in said opening relative to said guide plate, said housing and said rear plate defining a pumping chamber therebetween, said housing having inlet and outlet openings therein in communication with said chamber;
a driving shaft extending through said aperture in said rear plate into said pumping chamber;

an impeller mounted on said shaft in said chamber, said impeller having a plurality of radially extending flexible blades, said blades being in engagement with, and flexed by, the interior wall of said housing; an adjusting plate mounted on said guide plate, said adjusting plate having an aperture therein for receiving said housing; and

means cooperating with said adjusting plate and said guide plate to cause said adjusting plate and said housing to move laterally with respect to said guide plate when said adjusting plate is rotated.

3. A variable flow pump comprising:
a supporting plate for supporting said pump;
a rear plate mounted on said supporting plate, said rear plate having an aperture therein;
a guide plate mounted on said rear plate, said guide plate having a generally rectangular opening formed therein;
a housing slidably mounted in said generally rectangular opening, said housing and said rear plate defining a pumping chamber therebetween, said housing having inlet and outlet openings therein in communication with said chamber;
a driving shaft extending through said aperture in said rear plate into said pumping chamber;
an impeller mounted on said shaft in said chamber, said impeller having a plurality of radially extending flexible blades, said blades being in firm engagement with, and flexed by, the interior wall of said housing; and

an adjusting plate mounted on said guide plate, said adjusting plate having an aperture therein for receiving said housing, said adjusting plate having means cooperating with said guide plate to force said adjusting plate and said housing to move laterally with respect to said guide plate and said driving shaft when said adjusting plate is rotated whereby the pumping action of said pump is altered.

4. A variable flow pump comprising:
a supporting plate for supporting said pump;
a rear plate mounted on said supporting plate, said rear plate having an aperture therein;
a guide plate mounted on said rear plate, said guide plate having a generally rectangular opening formed therein;
a housing positioned over said guide plate and having shoulders thereon for cooperating with said rectangular opening whereby said housing may move in said opening relative to said guide plate, said housing and said rear plate defining a pumping chamber therebetween, said housing having inlet and outlet openings therein in communication with said chamber;
a driving shaft extending through said aperture in said rear plate into said pumping chamber;
an impeller mounted on said shaft in said chamber, said impeller having a plurality of radially extending flexible blades, said blades being in firm engagement with, and flexed by, the interior wall of said housing; and

an adjusting plate mounted on said guide plate, said adjusting plate having an aperture therein for receiving said housing in engaging relationship, said adjusting plate having means cooperating with said guide plate to force said adjusting plate and said housing to move laterally with respect to said guide plate and said driving shaft when said adjusting plate is rotated whereby the pumping action of said pump is altered.

5. A variable flow pump comprising:
a supporting plate for supporting said pump;
a rear plate mounted on said supporting plate, said rear plate having an aperture therein;
a guide plate mounted on said rear plate, said guide plate having a generally rectangular opening formed therein;

a housing positioned over said guide plate and having shoulders thereon for cooperating with said rectangular opening whereby said housing may move in said opening relative to said guide plate, said housing and said rear plate defining a pumping chamber therebetween, said housing having inlet and outlet openings therein in communication with said chamber; 5
a driving shaft extending through said aperture in said rear plate into said pumping chamber;
an impeller mounted on said shaft in said chamber, said 10 impeller having a plurality of radially extending flexible blades, said blades being in firm engagement with, and flexed by, the interior wall of said housing;
an adjusting plate mounted on said guide plate, said 15 adjusting plate having an aperture therein for receiving said housing in engaging relationship, said adjusting plate having means cooperating with said guide plate to force said adjusting plate and said housing to move laterally with respect to said guide plate and said driving shaft when said adjusting plate is rotated whereby the pumping action of said pump is altered;
a cap mounted on said housing and having inlet and outlet ports communicating with said inlet and outlet opening in said housing; and
20 a locking bar pivotally mounted on said supporting plate and cooperating with said cap to maintain said cap, housing, guide plate and rear plate on said supporting plate.

6. A variable flow pump comprising:

a supporting plate for supporting said pump;
a rear plate mounted on said supporting plate, said rear plate having an aperture therein;
a guide plate mounted on said rear plate, said guide plate having a generally rectangular opening formed 35 therein;
a housing positioned over said guide plate and having shoulders thereon for cooperating with said rectangular opening whereby said housing may move in said opening relative to said guide plate, said housing and 40 said rear plate defining a pumping chamber therebetween, said housing having inlet and outlet openings therein in communication with said chamber;
a driving shaft extending through said aperture in said rear plate into said pumping chamber;
an impeller mounted on said shaft in said chamber, said 45 impeller having a plurality of radially extending flexible blades, said blades being in firm engagement with, and flexed by, the interior wall of said housing;
an adjusting plate mounted on said guide plate, said 50 adjusting plate having an aperture therein for receiving said housing in engaging relationship, said adjusting plate having a slot eccentric relative to said aperture formed therein near the periphery thereof;
a pin fixedly attached to said guide plate and extending through said slot and cooperating therewith to force 55 said adjusting plate and said housing to move laterally with respect to said guide plate and said driving shaft when said adjusting plate is rotated whereby the degree of flexing of said blades by said interior wall of said housing is changed and the pumping action of said pump is altered;
a cap mounted on said housing and having inlet and outlet ports communicating with said inlet and outlet opening in said housing; and
60 a locking bar pivotally mounted on said supporting plate and cooperating with said cap to maintain said cap, housing, guide plate and rear plate on said supporting plate.

7. A variable flow pump comprising:

a supporting plate for supporting said pump, said plate having a plurality of pins extending outwardly therefrom;
a rear plate mounted on said supporting plate and 75

having apertures for receiving said pins and a central aperture;
a guide plate mounted on said rear plate and having apertures for receiving said pins, said guide plate having a generally rectangular opening formed therein;
a housing positioned over said guide plate and having shoulders thereon for cooperating with said rectangular opening whereby said housing may move in said opening relative to said guide plate, said housing and said rear plate defining a pumping chamber therebetween, said housing having inlet and outlet openings therein in communication with said chamber;
a driving shaft extending through said central aperture in said rear plate into said pumping chamber;
an impeller mounted on said shaft in said chamber, said impeller having a plurality of radially extending flexible blades, said blades being in firm engagement with, and flexed by, the interior wall of said housing;
an adjusting plate mounted on said guide plate, said adjusting plate having an aperture therein for receiving said housing in engaging relationship, said adjusting plate having a slot eccentric relative to said aperture formed therein near the periphery thereof;
a pin fixedly attached to said guide plate and extending through said slot and cooperating therewith to force said adjusting plate and said housing to move laterally with respect to said guide plate and said driving shaft when said adjusting plate is rotated whereby the degree of flexing of said blades by said interior wall of said housing is changed and the pumping action of said pump is altered;
a cap mounted on said housing and having inlet and outlet ports communicating with said inlet and outlet opening in said housing; and
a locking bar pivotally mounted on said supporting plate and cooperating with said cap to maintain said cap, housing, guide plate and rear plate on said supporting plate.

8. A variable flow pump comprising:

a supporting plate for supporting said pump, said plate having a plurality of pins extending outwardly therefrom;

a rear plate mounted on said supporting plate and having apertures for receiving said pins and a central aperture;

a guide plate mounted on said rear plate and having apertures for receiving said pins, said guide plate having a generally rectangular opening formed therein;

a housing positioned over said guide plate and having shoulders thereon for cooperating with said rectangular opening whereby said housing may move in said opening relative to said guide plate, said housing and said rear plate defining a pumping chamber therebetween, said housing having inlet and outlet openings therein in communication with said chamber;

a driving shaft extending through said central aperture in said rear plate into said pumping chamber;

an impeller mounted on said shaft in said chamber, said impeller having a plurality of radially extending flexible blades, said blades being in firm engagement with, and flexed by, the interior wall of said housing;

an adjusting plate mounted on said guide plate, said adjusting plate having an aperture therein for receiving said housing in engaging relationship, said adjusting plate having a generally arcuate slot eccentric relative to said aperture formed therein near the periphery thereof;

a pin fixedly attached to said guide plate and extending through said slot and cooperating therewith to force said adjusting plate and said housing to move laterally with respect to said guide plate and said driving shaft.

- shaft when said adjusting plate is rotated whereby the degree of flexing of said blades by said interior wall of said housing is changed and the pumping action of said pump is altered;
- a cap mounted on said housing and having inlet and outlet ports communicating with said inlet and outlet opening in said housing, said outlet port having a check valve positioned therein, said cap having a groove formed therein; and
- a locking bar pivotally mounted on said supporting plate and cooperating with said groove in said cap to maintain said cap, housing, guide plate and rear plate on said supporting plate.
9. The pump of claim 2 wherein said cooperating

means comprises a slot formed in said adjusting plate eccentric relative to said aperture and a pin mounted on said guide plate and extending into said slot.
